UNITED STATES PATENT OFFICE.

MENELAUS G. MURUFAS, OF LOS ANGELES, CALIFORNIA, ASSIGNOR OF ONE-HALF TO
JAMES RAISIS, OF SAN FRANCISCO, CALIFORNIA.

CHROMO ROLLER FOR PRINTING PRESSES.

Application filed September 15, 1921. Serial No. 500,842.

To all whom it may concern:

Be it known that I, MENELAUS G. MURUFAS, a subject of the King of Greece, residing at Los Angeles, in the county of Los Angeles and State of California, have invented new and useful Improvements in Chromo Rollers for Printing Presses, of which the following is a specification.

This invention relates to chromo rollers for printing presses and has for its object to provide certain improvements over my Patent No. 1,353,662, the general objects of which are the same for my present application.

More specifically, the object of this invention is to provide novel means whereby the upper inking disk will be rotated so as to evenly distribute the ink upon the rollers which could not be done satisfactorily by using a stationary disk as in my forementioned patent.

Other objects and advantages will be seen and the invention readily understood from the following description of the accompanying drawings in which:

Fig. 1 is a sectional front elevation of a Gordon press looking rearwardly from the front of the chase.

Fig. 2 is a side elevation of Fig. 1.

Fig. 3 is a plan view showing the lower disk and the frame and supporting plate for rotatably supporting the upper disk.

Fig. 4 is a bottom plan of the upper disk.

Fig. 5 is a view taken on line 5—5 of Fig. 3.

My improved device is shown as incorporated in a Gordon or any other suitable type of press adapted to employ the same. The press comprises substantially a bed 1 with the usual pawl and ratchet mechanism adapted to be actuated by the roller carrier 3 pivotally mounted upon the bed 1 so as to engage a lever arm 4 for actuating the rotating mechanism of the disk 2.

The usual sets of rollers are shown at 5 and 6 yieldably carried by the roller carrier so as to properly function when rolled over the chase and inking disk. Like the construction in my forementioned patent, usual roller tracks 7 are mounted so as to guide the rollers 6 upon the same and over the upper disk 8. As shown in the drawing, the disk 8 is supported upon arms 9 which are suitably supported upon the bed 1 and these

arms extend rearwardly and then form an upwardly extending loop, then project forwardly and the space 10 can be, if desired, utilized for the positioning of an ink fountain for the lower roller.

The supporting arms are shown as two in number in Fig. 1 and having laterally extending supporting members 11 to which is fastened the guide tracks 7. The supports 11 can also provide suitable supports for positioning of an ink fountain for the upper disk.

A suitable bearing support for the upper disk is provided as by having a plate 12 fastened upon the forwardly extending position of the arms 9 and an aperture 13 in said plate is adapted to receive the downwardly projecting spindle 14 of the disk 8 and is suitably spaced therefrom as by a spacing washer 15 and this being held in position by any suitable means here shown as a nut 16 having threaded engagement with the spindle on the other side of the plate 12.

Means for rotating the upper disk are provided by having the outer portion of the lower side of the disk notched as at 17, to provide a ratchet, these notches forming a shoulder and a tapering side so that a pawl 18 will only have engagement with the disk 8 in one direction. The pawl 18 is shown as pivotally mounted upon a support 19 suitably fastened to the members 11. A retractile spring 20 is fastened to the pawl 18 and member 11 so as to normally hold the same in rearward position which causes an actuating arm 21 extending from the pawl to be drawn in a forward position, and extending forwardly from the arm 21 is a roller engaging finger 22 adapted to actuate the pawl when the rollers 6 are passed up over the plate 8. The rollers 6 have outer guide wheels 23 adapted to roll upon the track 7 and it is one of these wheels that engages the finger 22.

In the operation the rollers will pass up onto the upper plate and hold the same against rotation and continual movement of the rollers will cause engagement with the finger 22 which will allow the pawl to slip back and engage a forward notch, then when the rollers are passed off the disk the spring 20 will pull the pawl so as to rotate the disk but it will thus be seen that successive operations of the rollers will cause

complete rotation of the disk and thereby insuring even distribution of ink upon the rollers.

Various changes may be made in the details of construction by those skilled in the art without departing from the spirit of my invention as set forth in the appended claims.

What is claimed is:

1. In a printing press, a rotatable disk spaced above the usual inking plate, a ratchet carried by said spaced disk, a pawl mounted on the frame of said press adapted to engage said ratchet, means carried by the inking rollers of said spaced disk adapted to actuate said pawl in non-engaging direction with said ratchet when passing over said spaced disk, yieldable means for causing engagement of said pawl and ratchet and to partially rotate said spaced disk when said rollers pass off of the same.

2. In a printing press, a pair of arms having extremities bent upon themselves, a plate

secured to the arms, a disk rotatable on the plate, teeth formed on the disk, a spring 25 pressed pawl engageable with teeth for effecting rotation of the disk, an actuating arm connected to the pawl, tracks at opposite sides of the disk, inking rollers movable between the tracks, and guide rollers carried by the inking rollers and movable over said tracks, certain of said guide rollers being engageable with said actuating arm for effecting actuation of said pawl.

3. In a printing press, a rotatable disk, 35 tracks at the opposite sides of the disk, inking rollers movable between the tracks, guide rollers carried by the inking rollers and movable over said tracks, and pawl and ratchet actuating means for said disk including an 40 arm disposed in the path of movement of certain of said guide rollers.

In testimony whereof I have signed my name to this specification.

MENELAUS G. MURUFAS.
